UNITED STATES PATENT OFFICE.

GEORGE W. MCKAY, OF PORTLAND, OREGON.

TOY HOOP.

1,162,868.

Specification of Letters Patent.

Patented Dec. 7, 1915.

Application filed April 1, 1915. Serial No. 18,550.

To all whom it may concern:

Be it known that I, GEORGE W. MCKAY, a citizen of the United States, residing at Portland, in the county of Multnomah,

5 State of Oregon, have invented certain new and useful Improvements in Toy Hoops; and I do hereby declare the following to be a full, clear, and exact description of the invention, such as will enable others skilled in 10 the art to which it appertains to make and use the same.

This invention relates to improvements in toys and particularly to rolling hoops.

The principal object of the invention is to 15 provide a rolling hoop with a guiding means by means of which the hoop is manufactured to retain a ball within the hoop.

Another object is to provide a hoop of 20 similar construction for holding the marble or ball therein.

Other objects and advantages will be apparent from the following description when taken in connection with the accompanying drawing.

25 In the drawing: Figure 1 is a side elevation of a hoop made in accordance with my invention, Fig. 2 is an enlarged vertical section on the line 2—2 of Fig. 1, Fig. 3 is a perspective view of the guiding and rolling device, and Fig. 4 is a horizontal section on the line 4—4 of Fig. 1.

Referring particularly to the accompanying drawing, 10 represents a hoop which is formed of a strip of metal, the marginal 30 edges of which are bent inwardly as at 11, and then directed in parallel spaced relation with their inner edges disposed toward the

center of the hoop, as clearly indicated at 12. Arranged to roll on and between these inwardly directed flanges 12 is a ball or 40 marble 13.

To roll the hoop there is provided a stick 14 in one end of which is secured a rectangular loop 15, one of the outer corners of which is separable, as shown at 16 to permit 45 of the placing of a portion of the hoop within the loop.

In the operation of the device, the loop 15 is properly engaged with the hoop and then the marble 13 placed so that it rests on the 50 two flanges 12. Then by manipulating the stick, the hoop can be caused to roll along the ground. By the exercise of skill, the hoop can be rolled so as to retain the marble 55 within the channel between the flanges 12.

Thus there is provided a simple and cheap device and one which will afford amusement, while at the same time requiring the exercise of skill and care.

What is claimed is:

60 A rolling hoop comprising a body portion having its marginal edge portions directed laterally and inwardly toward the center of the hoop to provide an interiorly arranged annular channel, a spherical object disposed 65 in rolling contact within the channel and a detachable hoop rolling and guiding means.

In testimony whereof, I affix my signature, in the presence of two witnesses.

GEORGE W. MCKAY.
